(57) **CLAIM**

I claim the ornamental design for a charging dock assembly, as shown and described.

DESCRIPTION

FIG. 1 is a front perspective view of a charging dock assembly, showing my new design;
FIG. 2 is a rear perspective view thereof;
FIG. 3 is a bottom perspective view thereof;
FIG. 4 is a front elevational view thereof;
FIG. 5 is a rear elevational view thereof;
FIG. 6 is a left side view thereof;
FIG. 7 is a right side view thereof;
FIG. 8 is a top plan view thereof;
FIG. 9 is a bottom plan view thereof; and,
FIG. 10 is a front perspective view of the charging dock assembly in a detached state.
The broken lines in the figures are for the purposes of illustrating portions of the charging dock assembly which form no part of the claimed design.
